UNITED STATES PATENT OFFICE.

GEORGE C. KNAUFF, OF CHICAGO, ILLINOIS.

CONNECTOR-PLUG.

1,088,997.

Specification of Letters Patent.

Patented Mar. 3, 1914.

Application filed May 26, 1913. Serial No. 769,947.

To all whom it may concern:

Be it known that I, GEORGE C. KNAUFF, citizen of the United States, residing at Chicago, in the county of Cook and State of Illinois, have invented certain new and useful Improvements in Connector-Plugs; and I do hereby declare the following to be a full, clear, and exact description of the invention, such as will enable others skilled in the art to which it appertains to make and use the same.

My invention relates to wire-attaching plugs and more particularly to the class of plugs suitable for use with automobile lamp sockets in which the connection to one terminal of the lamp is made through the socket casing.

One object of my invention is to provide a simple construction by which a metal shell housing the end portion of the plug may be connected to one wire of the circuit and by which the said shell may be interlocked with the socket when operatively connected to the socket.

Another object is to provide simple means for electrically connecting the central terminal of the plug with the other wire of the circuit and for securing the insulating member between this central terminal and the heretofore mentioned shell of the plug.

I accomplish these objects by the construction shown in the accompanying drawings, in which—

Figure —1— is a longitudinal section through an attachment plug embodying my invention. Fig. —2— is a similar section through an alternative embodiment of my invention and a portion of the socket casing interlocked therewith. Fig. —3— is an enlarged detail view of the portion of the shell of the plug having the interlocked formation thereon. Fig. 4 is a fragmentary view of a socket, lamp and plug embodying my invention.

In Fig. —1— the plug of my invention comprises an insulating body 1 having a pair of longitudinal bores 2 therein, and having one end externally threaded to match female threads upon a cap 3. The other end of the plug has a cylindrical exterior adapted to receive one end of a cylindrical brass or copper shell 4, which shell is secured to the plug by a screw 5 threaded transversely into a brass terminal 6 housed in one of the bores 2, whereby the screw 5 forms an electrical connection between the shell 4 and the

terminal 6. The shell 4 is of such diameter as to slidably interfit the end of the casing 21 of the socket to which the plug is to be attached, sockets suitable for use with the 60 plugs of my invention preferably having their casings equipped with spring fingers as shown in my copending patent application, Serial No. 769,948, filed May 26, 1913. Inserted in the other bore of the insulating 65 body 1 is a terminal 7 having an enlarged head portion 8 adjacent to the end of the body 1 which is housed by a portion of the shell 4, this portion 8 and a part of the terminal 7 adjacent thereto being bored out to 70 form a cylinder for housing a brass or copper piston 9. The piston 9 is pressed outwardly by a spring 10, whereby the plunger 11 of the piston projecting through a perforation in the head 8 is forced against a 75 peripheral portion of the head 12 of a contact member 13, which contact member is disposed axially of the plug.

Interposed between the shank of the contact member 13 and the shell 4 is a cylinder 80 14 of insulating material, which cylinder has its outer periphery chamfered to match the correspondingly diagonal shape of a contracted portion 15 at the forward end of the shell 4. Each of the terminals 6 and 7 has 85 at its rear end a perforation 16 adapted to receive the bared end of one of the wires 17 and 18 of the circuit, which wires enter the cap 3 through an opening 19 in the rear end thereof. The shell 4 has intermediate 90 of its ends a pair of diametrically opposite projections 20 formed thereon, the latter being preferably formed by setting the shell into a die having a perforation therein corresponding to the desired outside diameter 95 of the said projection, and by then forcing the adjacent portion of the shell into this perforation with a punch of considerably smaller diameter than the said perforation. When the opposed formations 20 have thus 100 been raised upon the surface of the shell 4, they constitute lugs or perforations adapted to enter the slots 24 in the casing 21 of the socket with which the plug is to be used, the slots of this socket preferably having enlargements or notches 25 forming bayonet catches after the manner common in socket construction.

Instead of using a spring pressed plunger 8 for making the electrical connection 110 between the contact member 13 and the wire terminal 7, one end of the latter may be

riveted directly to the head 12 of the said contact member, as shown in Fig. —2—. In either case, it will be evident that no great exactness of fit will be required between the auxiliary insulating cylinder 14 and the members separated by the same; also that the screw 5 constitutes a metallic fastening member which simultaneously fastens the shell 4 to the body of the plug and grounds the terminal 6 to the shell 4, while the outward punching of the portion 20 enables me to make the retaining lugs of the plug integral with the shell, so that they cannot work loose. It will also be obvious that when the connector plug of my invention is used with a socket having a metal casing 21 contactingly interfitting the metal shell 22 of a lamp 23, which shell is connected to one end of the filament of the lamp, the said end of the lamp filament is electrically connected through the shell 22, casing 21, screw 5 and terminal 6 to one wire 17 of the circuit.

I claim as new and desire to cover by Letters Patent:

- 25 1. In a wire-connecting plug for a socket having a metal casing, an insulating body; a pair of wire terminals carried thereby; a metal shell mounted upon one end of the insulating body, the said shell slidingly interfitting the casing of the socket and electrically connected to one of the wire terminals; an auxiliary insulating body housed within the said shell; a contact member carried by the auxiliary insulating body; the outer end of the said shell being contracted to secure the auxiliary insulating body and the contact member carried thereby within the said shell; and a spring-pressed member interposed between the contact member and the other of the said wire terminals.
- 30 2. In a wire-connecting plug for a socket having a metal casing, a main insulating body; a pair of wire terminals carried thereby; a metal shell mounted upon one end of the insulating body, the said shell slidingly interfitting the casing of the socket and electrically connected to one of the wire terminals; an auxiliary insulating body housed within the said shell; and a contact member carried by the auxiliary insulating body and electrically connected to the other of the
- 35 3. In a wire-connecting plug for a socket having a metal casing, an insulating body; a pair of wire terminals carried thereby; a metal shell mounted upon one end of the insulating body, the said shell slidingly interfitting the said casing of the socket and electrically connected to one of the wire terminals; an auxiliary insulating body housed within the said shell; and a contact member carried by the auxiliary insulating body and electrically connected to the other of the
- 40 4. In a wire-connecting plug for a socket having a metal casing, a main insulating body; a pair of wire terminals carried thereby; a metal shell mounted upon one end of the insulating body, the said shell slidingly interfitting the casing of the socket and electrically connected to one of the wire terminals; an auxiliary insulating body housed within the said shell; and a contact member carried by the auxiliary insulating body and electrically connected to the other of the
- 45 5. In a wire-connecting plug for a socket having a metal casing, an insulating body; a pair of wire terminals carried thereby; a metal shell mounted upon one end of the insulating body, the said shell slidingly interfitting the casing of the socket and electrically connected to one of the wire terminals; an auxiliary insulating body housed within the said shell; and a contact member carried by the auxiliary insulating body and electrically connected to the other of the
- 50 6. In a wire-connecting plug for a socket having a metal casing, an insulating body; a pair of wire terminals carried thereby; a metal shell mounted upon one end of the insulating body, the said shell slidingly interfitting the said casing of the socket and electrically connected to one of the wire terminals; an auxiliary insulating body housed within the said shell; and a contact member carried by the auxiliary insulating body and electrically connected to the other of the

said wire terminals, the outer end of the said shell being contracted to secure the auxiliary insulating body within the said shell.

3. In a wire-connecting plug for a socket having a metal casing, an insulating body; a pair of wire terminals carried thereby; a metal shell mounted upon one end of the insulating body, the said shell slidingly interfitting the said casing of the socket; a metallic fastening member electrically connecting the said shell and one of the wire terminals carried by the insulating body, the said fastening member extending through a portion of the insulating body and thereby securing both the shell and the last-named wire-terminal to the insulating body; and a contact member mounted within the said shell and insulated therefrom and electrically connected to the other of the said wire terminals.

4. In a wire-connecting plug for a socket having a metal casing, a main insulating body; a pair of wire terminals carried thereby; a metal shell mounted upon one end of the insulating body, the said shell slidingly interfitting the casing of the socket and electrically connected to one of the wire terminals; an auxiliary insulating body housed within the said shell; and a contact member carried by the auxiliary insulating body and electrically connected to the other of the

5. In a wire-connecting plug for a socket having a metal casing, an insulating body; a pair of wire terminals carried thereby; a metal shell mounted upon one end of the insulating body, the said shell slidingly interfitting the casing of the socket and electrically connected to one of the wire terminals; a contact member insulatingly mounted within the said shell; and a spring-pressed member interposed between the contact member and the other of the said wire terminals.

In testimony whereof I have signed my name in presence of two subscribing witnesses.
